United States Patent Office

Des. 189,210
Patented Nov. 8, 1960

189,210

HAND LEVEL OR SIMILAR ARTICLE

Elwin W. Davis, La Vale, Md., assignor to C. L. Berger & Sons, Inc., Boston, Mass., a corporation of Massachusetts

Filed Apr. 30, 1959, Ser. No. 55,705

Term of patent 14 years

(Cl. D52—1)

Figure 1 is view in perspective of a hand level or similar article, showing my new design.

I claim:

The ornamental design for a hand level or similar article, substantially as shown and described.
